Patented May 16, 1967

207,629

BRASSIERE

Charles M. Sachs, West Englewood, and Edward Jannicelli, Jr., Ramsey, N.J., assignors to International Playtex Corporation, a corporation of Delaware

Filed Feb. 10, 1966, Ser. No. 993

Term of patent 14 years

(Cl. D2—24)

The essential features of our design reside in the full-line disclosure on the drawings.

We claim:

The ornamental design for a brassiere, as shown and described.
